United States Patent Office

Des. 178,755
Patented Sept. 18, 1956

178,755

SMALL TABLE COVERING

Thomas William Binns, Huntingdon Valley, Pa., assignor to Quaker Lace Company, Philadelphia, Pa.

Application December 21, 1955, Serial No. 39,418

Term of patent 7 years

(Cl. D92—26)

The figure is a plan view of a small table covering, showing my new design. The table covering is shown over a dark background to bring out the details of the design.

I claim:

The ornamental design for a small table covering, substantially as shown and described.
